UNITED STATES PATENT OFFICE.

JOHN H. GRAYSON, OF ATHENS, OHIO, ASSIGNOR TO THE J. H. GRAYSON MANUFACTURING COMPANY, OF ATHENS, OHIO, A CORPORATION OF OHIO.

DESIGN FOR A GAS HEATER.

Application filed May 7, 1924. Serial No. 9,516. Term of patent 14 years.

To all whom it may concern:

Be it known that I, JOHN H. GRAYSON, a citizen of the United States, residing at Athens, in the county of Athens and State of Ohio, have invented a new, original, and ornamental Design for Gas Heaters, of which the following is a specification, reference being had to the accompanying drawing, forming part thereof, and wherein—

Fig. 1 is a front view of the heater; and

Fig. 2 is a side view of the same.

I claim:

The ornamental design for a gas heater, as shown.

JOHN H. GRAYSON.
